UNITED STATES PATENT OFFICE

JOHN J. KEEFE, OF SAN ANTONIO, TEXAS

SHOWER BATH

Application filed May 28, 1930. Serial No. 456,430.

This invention relates to shower baths especially adapted for use in public bath houses although not necessarily restricted to such use.

5 Briefly stated, an important object of this invention is to provide simple means by which the weight of a bather on a depressible platform brings about the opening of a shower controlling valve with the result that the discharge of water from the shower is accomplished and immediately upon the removal of the weight of the bather from the platform the discharge of water is stopped, it being noted that such an arrangement has the effect of conserving water and the germicidal solution with which the water may be impregnated.

10 A further and equally important object of the invention is to provide an automatic shower in which the supporting means for the depressible platform is arranged to hold the platform against canting and possible binding as a result of the unequal distribution of weight thereon.

15 25 Another aim of the invention is to provide a shower bath of the character described which is of highly simplified construction, comparatively cheap to manufacture and which is of sufficiently rugged construction to withstand the abuse to which showers are subjected in public and other places.

20 Other objects and advantages will be apparent during the course of the following description.

30 35 In the accompanying drawings forming a part of this application and in which like numerals are employed to designate like parts throughout the same,

40 45 Figure 1 is a vertical sectional view through the improved shower, illustrating the means by which an antiseptic is introduced into the water supply.

Figure 2 is a horizontal sectional view taken on line 2—2 of Figure 1,

45 50 Figure 3 is a detail sectional view illustrating one of the means for yieldingly supporting the platform, the view being taken on line 3—3 of Figure 2,

50 55 Figure 4 is a vertical sectional view through

the shower, the view being taken at right angles to Figure 1,

Figure 5 is an enlarged detail vertical sectional view illustrating the valve operating means.

60 65 In the drawings wherein for the purpose of illustration is shown a preferred embodiment of the invention, the numeral 5 designates a structure such as a bath house and within which an enclosure 6, forming the shower bath may be located. Figures 1 and 2 illustrate that access to the enclosure 6 is afforded by a doorway having doors 7. The opposite side 8 of the shower bath may be open for the egress of the bathers.

65 70 75 The shower is provided with a water distributing system comprising a main supply pipe 10 into which a suitable antiseptic from a source of supply 12 may be introduced in any desired proportion to the volume of water fed to the shower. As the introduction of the antiseptic into the water may be accomplished in any one of a variety of ways and forms no special part of the invention, no detailed disclosure of this will be found in this application.

75 80 85 The main supply pipe 10 extends beneath a depressible platform 14 and is provided with a gate valve 16 by which the flow of water through the several branch pipes 20 is controlled. As shown in Figure 4, the branch pipes 20 extend up along the sides and across the top of the enclosure 6 and are provided with shower heads 22. Figure 4 further illustrates that the shower heads 22 are positioned to direct sprays downward and horizontally on the person standing on the platform 14 so that equal and complete coverage is obtained.

90 95 The platform 14 is preferably of rectangular formation and has connection at each corner thereof with a supporting stud 26, the upper portion of which extends through an opening in the platform. Figure 3 illustrates that upper and lower flanges 27 and 28 respectively are secured to opposite surfaces of the platform through the medium of fastening bolts 30 and have the openings therein in alignment with the adjacent opening in the platform. In carrying out the

invention, the lower flange is provided in the underside thereof with a depending rib constituting a guide for an expansion spring 32, the lower portion of which engages a thimble 34 resting on the base 36. It is believed to be apparent that the expansion 5 spring 32 which encircles the stud 26 cooperates with a second coil spring 40 in urging the platform 14 to the elevated position disclosed in Figure 1.

The lower portion of the expansion spring 40 is nested in, and is supported by, a thimble or annulus 42 mounted on the threaded upper portion of the stud 26. The thimble 15 42 is mounted on a stop nut 43 shown to be in the path of travel of and adapted to be engaged by the central portion of the lower flange 28 to limit upward movement of the platform under the influence of the springs 20 32 and 40.

Each expansion spring 40 is confined within a guide cylinder 46, the upper end of which is engaged with a cap 48 carried by the cylinder. Each cylinder 46 is threaded 25 through the adjacent upper flange 27 and is adjustable with respect thereto so that the effective strength of the upper spring 40 may be varied.

The downward movement of the platform 30 under the weight of a bather is limited by a set screw 49 carried by the cap and adapted to engage a contact member 52 secured on the upper portion of the stud 26 by a cap nut 54. It is preferred to have the contact 35 element 52 of a soft material such as lead, fiber, or rubber, so that the downward movement of the platform will be yieldingly arrested.

As best illustrated in Figures 4 and 5, a 40 yoke 55 is connected at the ends thereof to opposite sides of the platform and is provided with converging arms joined by a bight portion to which the stem 56 of the gate valve 16 is connected. It is believed to be apparent 45 that the depression of the platform will result in the opening of the gate valve 16 to bring about the discharge of water from the various shower heads 22 and that when the weight on the platform 14 is removed, the concerted action of the springs 32 and 40 at 50 the four corners of the platform will promptly return the platform to elevated position and thereby cut off the further discharge of water.

Figures 1 and 2 illustrate that the platform 55 14 is composed largely of a plurality of spaced, parallel, slat-like members defining passages or slots through which water may drain into a concrete drain pit 60, to be carried off by a drain pipe 61. It will be observed with special reference to Figures 1 and 4 that the yoke 55 is extended below the central portion of the platform and is received within the upper portion of the pit, 60 also that the main supply pipe 10 is disposed

at right angles to, and above the horizontal bight portion of, the yoke 55. The valve 16 located in the main supply pipe 10, is positioned directly above the bight portion of the yoke and is connected thereto by a depending 70 valve stem 56.

In the operation of the improved shower bath, the bather has only to enter the enclosure 6 and stand upon the platform 14 to bring about the downward movement of the 75 platform, whereupon the gate valve 16 is opened to allow of the flow of medicated water from the shower heads 22. The flow of water will continue as long as the person remains on the platform and when the shower has been completed the bather may leave by way of the opening 8 permitting the springs 80 32 and 40 to return the platform to its original elevated position whereupon the supply of water is cut off.

A shower bath constructed in accordance with this invention is of highly simplified construction and is sufficiently rugged to withstand the abuse to which public and other showers are subjected. Also, the arrangement is such that ready access to the various working parts, for example the gate valve, is afforded. Access to the gate valve may be afforded either by the removal of the central slats of the platform or by the removal of the entire platform.

It is to be understood that the form of invention herewith shown and described is to be taken merely as a preferred example of the same and that such minor changes in arrangement and construction of parts may be made as will remain within the spirit of the invention and the scope of what is claimed.

Having thus described the invention, what is claimed is:

1. In a shower bath, a platform, springs supporting the platform at the corners thereof and normally holding the same in elevated position, a supply pipe having means to discharge a bathing solution above said platform, a valve controlling the flow of fluid through said pipe and having a stem, and a yoke suspended from said platform and having a bight portion operatively connected to said stem.

2. In a shower bath, a platform, adjustable spring means at the corners of said platform to normally hold the same in an elevated position, a fluid supply pipe extending beneath said platform and having a valve provided with a stem, a yoke extending centrally beneath said platform and connected to opposite sides of the same, said yoke being provided with a horizontally disposed portion connected to said stem to operate the valve, and shower heads having connection with said fluid supply pipe.

3. In a shower bath, a rectangular platform, adjustable springs located at the corners of the platform and normally holding

the same in an elevated position, a yoke extending centrally beneath said platform and connected to opposite sides of the same, a fluid conducting pipe extending beneath the platform at right angles to said yoke and being provided with a valve, means establishing an operative connection between the valve and the yoke, and outlet members connected to said fluid supply pipe.

4. In a shower, a platform, means yieldingly holding the platform in an elevated position, a fluid supply pipe extending beneath the platform, a valve for said pipe and having a depending actuating stem, a yoke extending at right angles to said pipe and being provided with a horizontally disposed bight portion underlying said valve and connected to the stem thereof to operate the stem, said fluid supply pipe having branches provided with spray heads.

5. In a structure of the class described, a platform having an opening, a supporting stud in said opening, upper and lower flanges secured to opposite sides of said platform at opposite ends of said opening, a spring engaged with said lower flange to urge the platform upward, and a stop nut on the upper portion of said stud and located in the path of travel of and adapted to be engaged by said lower flange to limit upward movement of the platform.

6. In a structure of the class described, a platform having an opening, a supporting stud in said opening, upper and lower flanges secured to opposite sides of said platform at opposite ends of said opening, a spring engaged with said lower flange to urge the platform upward, a stop nut on the upper portion of said stud and located in the path of travel of and adapted to be engaged by said lower flange to limit upward movement of the platform, a cylinder threaded through said upper flange and having a cap, and a second spring confined between said cap and stop nut and acting in concert with said first named spring to urge the platform upward.

7. In a structure of the class described, a platform having an opening, a supporting stud in said opening, upper and lower flanges secured to opposite sides of said platform at opposite ends of said opening, a spring engaged with said lower flange to urge the platform upward, a stop nut on the upper portion of said stud and located in the path of travel of and adapted to be engaged by said lower flange to limit upward movement of the platform, a cylinder threaded through said upper flange and having a cap, a second spring confined between said cap and said stop nut and acting in concert with said first named spring to urge the platform upward, and a set screw carried by said cap, said stud being provided with a cushion in the path of travel of and adapted to be engaged by said set screw to cushion the descent of said platform.

8. In a structure of the class described, a platform having an opening, a supporting stud in said opening, upper and lower flanges secured to opposite sides of said platform at opposite ends of said opening, a spring engaged with said lower flange to urge the platform upward, a stop nut on said stud and located in the path of travel of and adapted to be engaged by said lower flange to limit upward movement of the platform, a cylinder threaded through said upper flange and having a cap, and a second spring confined between said cap and said stop nut and acting in concert with said first named spring to urge the platform upward, said cylinder being adjustable with respect to said flange to allow the tension of said second named spring to be varied.

9. In a structure of the class described, a platform having an opening, a supporting stud extending into said opening, a spring beneath said platform and urging the same upward, a stop nut on said stud and located within said opening, a stop member on said nut, a spring engaged with said stop member, a cylinder receiving said second named spring and having a stop therefor, and means carried by said cylinder and said stud to limit the descent of said platform, said stud being positioned within said cylinder.

10. In a structure of the class described, a platform having an opening, a supporting stud extending into said opening, a spring beneath said platform and urging the same upward, a stop nut on said stud and located within said opening, a stop member on said nut, a spring engaged with said stop member, a cylinder receiving said second named spring and having a stop therefor, and means carried by said cylinder and said stud to limit the descent of said platform, said stud being positioned within said cylinder, there being means associated with said stud and said platform to limit the upward movement of the platform under the influence of said first and second named springs.

In testimony whereof I affix my signature.

JOHN J. KEEFE.
